UNITED STATES PATENT OFFICE

2,549,933

VIBRATORY WEIGHT REDUCER

William A. Rohlfs, Lancaster, Pa.

Application October 10, 1947, Serial No. 779,133

2 Claims. (Cl. 68—4)

1

My invention relates to devices for enabling the user thereof to reduce weight by the removal of surplus flesh and relates more particularly to such devices which accomplish the desired result by means of a vibratory belt which partially encircles the user and has its ends connected to a suitable source of power including means for vibrating the belt.

Many domestic washing machines are provided with an impeller so driven by a motor that the impeller has imparted to it a rapid oscillatory movement. I have found that such movement is satisfactory to actuate a weight reducing vibrator.

With the foregoing in view an object of my invention is to provide an improved weight reducer of the class described.

A further object is to provide means for coupling a vibrator to an oscillating impeller of a washing machine.

A further object is to provide a novel body encircling belt for a vibratory weight reducer.

Other objects and advantages reside in the particular structure of the invention, the combination and arrangement of the several parts thereof and will be readily apparent to those skilled in the art upon reference to the attached drawings in connection with the following specification wherein the invention is shown, described and claimed.

In the drawings:

Figure 1 is a front elevation of a belt of the invention apart from the coupling device;

Figure 2 is an elevation of the coupling of the invention apart from the belt;

Figure 3 is a plan view of the coupling apart from the belt;

Figure 4 is a plan view of a washing machine showing the belt and coupling in assembled relation and attached operatively to the washing machine;

Figure 5 is a transverse vertical section taken substantially on the plane of the line 5—5 of Figure 4.

Referring specifically to the drawings, wherein like reference characters have been used throughout to designate like parts, 10 designates an endless elastic member of any suitable material formed to provide an elongated top run 11 and an elongated bottom run 12 connected together by relatively short end bights 13 and 14. Substantially identical straps 15 are connected to the bights 13 and 14 and such straps are preferably formed of elastic material. Any suitable readily detachable connecting members such as

2

the snap hooks 16 are carried by the free ends of the straps 15.

A plurality of body engaging rollers 17 are mounted between the upper and lower runs 11 and 12 of the member 10 in laterally spaced relation on parallel axes which are substantially at right angles to the upper and lower runs aforesaid. The rollers 17 are rollably mounted on pivot members 18 which connect the upper and lower runs aforesaid and which may comprise any suitable flexible members such as rubber cord or rubber covered wire.

Referring specifically to Figures 4 and 5, 20 designates generally any typical home washing machine having a tub 21 and a drive shaft 22 which is adapted to be oscillated by any suitable motor, not shown. An impeller 23 is operatively connected to the drive shaft 22 for oscillation therewith and is provided with a plurality of 20 radially extending impeller blades 24.

Figures 2, 3, 4 and 5 illustrate a coupling member for attaching the belt 19 to the impeller 23. Such coupling member may comprise an inverted cup-shaped device or housing having cylindrical side walls 25 provided at the bottom edge with a plurality of inwardly and upwardly directed slots 26 which are adapted to fit over the impeller blades 24. Suitable clamping means such as the set screws 28 may be extended from the coupling member to clamp the same to the impeller 23. The coupling member is provided with a substantially circular top wall 27 which has secured thereto in any suitable manner a cross-head or bar 29 which extends outwardly beyond the planes of the walls 25. Centrally of the cross-head 29 and axially of the coupling member there is provided an upstanding swivel eye 30 to which are attached the inner ends of a pair of elastic stabilizing members or straps 31, the outer ends of which are provided with any suitable securing members such as the hooks 32 which are adapted to extend from the cross-head at substantially right angles thereto and engage over the rim 34 of the tub 21. The free ends of the cross-head 29 are formed to provide suitable means such as the apertures 33 for detachably connecting the hooks 16 of the belt thereto.

It follows from the foregoing, that as the impeller 23 is oscillated with the shaft 22 the coupling member, which extends upwardly above the top of the tub 21, will be oscillated as will the cross-head 29. Such oscillatory motion is transmitted by the cross-head to the belt 10 and the latter will be oscillated or vibrated therewith.

The rollers 17 of the belt prevent injury to the user when the belt is partially encircled around the body or a body member of the user whereby to beneficially massage the body and remove superfluous flesh by such massage. It is to be understood in this connection, that the oscillation or vibration of the belt 10 is extremely rapid and the benefits of the massage achieved thereby may be applied to any part of the body merely by shifting the belt thereon.

While I have shown a particular type of coupling means for a particular type of impeller 23, it is obvious that the coupling member is adapted to be modified to fit impellers of other shape and form. Consequently, while I have shown and described what is thought to be a preferred embodiment of the invention, it is understood that the same is susceptible of other forms and expressions and that I do not limit myself to the precise structures shown and described except as hereinafter claimed.

What is claimed is:

1. A power take-off coupling for attachment to an upstanding oscillatory impeller provided with radially extending blades and mounted in a washing machine tub, comprising, an upstanding housing arranged to partially enclose said impeller and having the lower end fixedly secured to said impeller for oscillation therewith, a bar positioned transversely of said housing adjacent the upper end of the latter and fixedly secured intermediate its ends to said housing, means on said bar adjacent each end thereof for attachment to an element to be oscillated, an upstanding swivel eye carried by said bar intermediate the ends thereof and at least two straps arranged in end to end facing relation and each having the facing

end secured to said swivel eye, the other end of each of said straps being provided with means for attachment to the rim of said tub.

2. A power take-off coupling for attachment to an upstanding oscillatory impeller provided with radially extending blades and mounted in a washing machine tub, comprising, an upstanding housing arranged to partially enclose said impeller and having the lower end provided with a plurality of spaced longitudinal slots extending inwardly thereof and embracingly engaging the adjacent portions of said blades for oscillation therewith, a bar positioned transversely of said housing adjacent the upper end of the latter and fixedly secured intermediate its ends to said housing, means on said bar adjacent each end thereof for attachment to an element to be oscillated, an upstanding swivel eye carried by said bar intermediate the ends thereof and at least two straps arranged in end to end facing relation and each having the facing end secured to said swivel eye, and a hook on the other end of each of said straps for attachment to the rim of said tub.

WILLIAM A. ROHLFFS.
